(57) **CLAIM**

I claim the ornamental design for an electronic cigarette package, as shown and described.

DESCRIPTION

FIG. 1 is a top, front, and side perspective view of an electronic cigarette package;

FIG. 2 is a front view thereof;

FIG. 3 is a back view thereof;

FIG. 4 is a top view thereof;

FIG. 5 is a bottom side view thereof;

FIG. 6 is a first side view thereof; and,

FIG. 7 is a second side view thereof.

In the drawings, the broken lines are for the purpose of illustrating environment only and form no part of the claimed design.
